UNITED STATES PATENT OFFICE.

JOHN LAUBE, OF MORGAN, MINNESOTA.

RAILWAY-CROSSING SIGNAL.

Application filed May 31, 1924. Serial No. 717,029.

To all whom it may concern:

Be it known that I, JOHN LAUBE, a subject of the King of England, residing at Morgan, in the county of Redwood and 5 State of Minnesota, have invented certain new and useful Improvements in Railway-Crossing Signals, of which the following is a specification.

My invention relates to danger signals in 10 general and more particularly a signaling device best adapted for highway and railway intersections or so-called crossings.

The object is to provide a highly efficient 15 audible and visible signal device operated by a moving train or engine approaching a crossing.

In the accompanying drawings:

Fig. 1 is a top view, in small scale, of my 20 device applied to a railway track crossed by a highway, the latter indicated in dotted lines only.

Fig. 2 is a front elevation of Fig. 1 omitting the near side rail and showing the far side rail as the latter would appear from 25 line 2—2 in Fig. 1.

Fig. 3 is an enlarged edge view of the signal post of my device looking in a direction parallel to the railway track.

Fig. 4 is a partly sectional front elevation 30 of Fig. 3, the section being taken about as on line 4—4 in Fig. 3.

Fig. 5 is an end view of the mechanism 35 housing of my device which is attached to a rail and housing the means acting directly on the signal apparatus shown in Figs. 3 and 4.

Fig. 6 is Fig. 5 as seen on line 6—6 in the latter figure.

Fig. 7 is a sectional elevation on line 7—7 40 in Fig. 5 exposing the mechanism within the box 35 fixed on the rail adjacent the signal apparatus.

Fig. 8 is a top view of Fig. 5 or Fig. 7 with the rail web shown in section.

Fig. 9 is a top view of a portion of a 45 track rail, part of the rail tread being omitted to disclose the mechanism secured to the rail and actuated by car wheels when moving over the track toward a crossing.

Fig. 10 is a rear elevation of Fig. 9 as 50 looking toward the latter from the upper end of the drawing sheet.

Fig. 11 is a side elevation of Fig. 9 looking from between the rails of a track.

Fig. 12 is a sectional elevation on the line

12—12 in Fig. 9 with the lug 73 in Fig. 9 omitted.

Fig. 13 is a section on line 13—13 in Fig. 6.

Fig. 14 is Fig. 13 modified. 60

Referring to the drawing by reference numerals, 15 designates ties and 16—16^a a pair of rails forming a railway track and 17 indicates a road crossing the track.

A suitable distance from the crossing I 65 secure in the ground a signal post 18 having a cap 19 as a part of means not completely shown for protecting the signaling element and the mechanism actuating the same from the elements. Of said mechanism or means 20 is a bell sounded by a clapper 21 having a spring arm 22 with a projection 23 over which may swing vertically an arm 24 of a lever 25 which is pivoted at

26 to the post and has a slotted hole 27 engaged by a pin 28 secured in a vertically reciprocating rod 29. Said rod extends down into a frame 30 fixed on the post and has there a nut 31 to limit its upward movement when thrown upward by a rocker arm 32 which has a slotted hole for the rod and is fixed on a horizontal rock shaft 33 journaled in suitable bearings in a tube 34 having one end secured in the frame 30 and the other end in a frame or housing 35, which with its mechanism will presently be 70 75 80

further described. Said mechanism is however such that any car wheel rolling over the rail toward the crossing will contact with it and impart a rocking movement of the 90 shaft 33 and thus throw the arm 32 up under a coil spring 36 on rod 29. The raising of the arm does not act directly on the rod but it mainly compresses the spring against a fixed collar or pin 37 and as the spring expands it raises the rod 29 and thereby rotates a ratchet wheel 38 by a dog 39 pivoted at 40 to a rocker arm 41 journaled on a stud 42 fixed in the post 18. 95

To the ratchet wheel or its hub 38^a is secured a colored signal board having two or more radial wings 43. Preferably, the pivot 40 holds both the dog 35 and the vertically forked rod 29; and the dog is normally held engaged with the ratchet wheel by a leaf spring 44; and on the post is adjustably secured a finger 45 with which the upper part of the dog, when lowered that far, will contact and thereby be disengaged from the ratchet wheel, so as to prevent un- 100 105 110

2
necessary wear of it and the dog while the signal board is spinning on the stud. By the time the board commences to rotate slowly another car wheel of the moving 5 train will give the rod 29 another upward jerk, and so on, until the train has passed the crossing. At the same time the arm 24 will have caused the clapper to sound the bell each time the arm 24 passes up or down 10 over the projection 24^a of the clapper arm. This explains the effect the rocking of shaft 33 has upon the visual and audible signal elements on the post 18. I will now describe more fully the means by which a moving train causes the shaft 33 to rock before it gets to the crossing, so as to warn all parties near the cross road to keep away from the railway track until the train has passed by.

20 The mechanism box or frame 35 is clamped to the side of the rail 16 by a clamping rod 46 (see Fig. 5) extending transversely under the rail and having at its inner end a rigidly fixed plate 47 with studs 48 placed in cavities in the frame 35, while the other end of the rod extends through a washer 49 and has a nut 50 for drawing the rod tight with the parts 47—35 in place. The washer 49 is curved as a clamp member 25 over the base flange of the rail.

Fixed on the inner end of shaft 33, in the housing 35, is a double-armed cam 51 whose upward arm is swung in one direction by a yoke 52 and a pulling rod 53 and in the 30 other direction by a contraction coil spring 54 disposed in a tubular spring guide and holder 55 the spring being connected by a nut 56 or other means. In like manner the lower cam arm 51 is actuated by a yoke 52^a 35 and spring 54^a in a tube 55^a. The rods 53 and 53^a are secured by couplings 57 to long rods 58 and 58^a respectively, supported slidably in guides 59 or 59^a (in Figs. 6, 13 and 40 14) to be further described and may extend 45 about six hundred feet along the rail, one rod in each direction from the road crossing 17. These rods 58 and 58^a being practically alike, a description of one of them will answer for both; it being understood however that the devices actuated by the car wheels so as to cause pulling of the rods are right and left or counterparts at each side of the road 17, so that the same 50 train operating the signal when approaching road 17 from either side of it will not operate the signal after having passed the crossing. This is the reason, in Fig. 1, each 55 wheel-contacting device has a lever 83 pointing to the left at one side of the road crossing 17 and pointing to the right at the other side of crossing 17, but otherwise the following description will explain it all.

The rod 58 (or 58^a) is made up of a few sections, say about two hundred feet long 60 each, and the adjoining ends of the sections

are guided in the angular end flanges 61—62 (see Figs 10—11—12 and 9) of a small frame 63, which has a channel 64 with a downward groove 65 (best shown in Fig. 12). In said channel the ends of the rod sections overlap 70 in any suitable, slidable manner. In the present drawing one section is bent to form an eye 66 with a vertical finger 67 guiding in the groove 65 of the channel 64; the other section having its end bent at right angles 75 forming a finger 68 that is engageable by a rocker arm 69 of a rock-shaft 70, which is journaled in a groove 71 in the upper side of a metal frame 72 placed under the base of the rail and is detachably secured to the 80 rail by having lugs 73 and 74 gripping upon the base flange at one side of the rail and a pair of hook bolts 75 extending through the frame 72 and provided with nuts 76, while their other ends form arms 77 secured 85 by screws 78 to the frame 63, whereby the said two frames 72 and 63 are firmly held in place on the rail.

The rock shaft 70 has a rocker arm 79 swingable up and down in a clearance 80 in frame 72 and near the said clearance 90 the frame has a flat, vertical arm 81 to which is secured by a pivot bolt 82 a lever 83 having at one end a weight 84 and at its other end a stud 85 on which is pivoted a T-shaped 95 stirrup 86 the head and arms of which are in the path of the guiding flange of any regular railway wheel running on the rail 16.

The operation of this sub-mechanism is 100 as follows:

A car wheel C coming in the direction of the arrow A in Fig. 11 will touch the arm B of the stirrup and tilt the leg L of it upon the arm 79 and then the wheel passes over the head H, presses downward and operates arms 79, 69, finger 68 and rod 58 and the signals, before reaching the crossing; but after passing the crossing the reversely arranged levers 83 and stirrups will be hit by the wheels, as the flange C² at the arm B², which being thereby depressed swings the leg L of the stirrup into the clearance 80 where its descent has no effect on the arm 79, and hence the signal is not operated by any train while it is moving away from the 110 crossing. A wheel coming in the direction of arrow A² will however operate all the stirrups it passes over before reaching the crossing because they all have their arms B turned toward A².

In Figs. 13 and 14 is shown how brackets 59 or 59^a are secured by washers 87 and nuts 88, and that the rod 58 may be guided either in a notch 89 close by the rail web or in a hole 90 in the bracket arm 125 some distance from the rail web. The latter is preferable where the rod 58 is to pass along the outside of the fish-plates of the rail joints; but in some cases where the fish plates are grooved adjacent the rail 130

pass the rod through said grooves and may then have such portion of the rod flat, as indicated at 58^x in Fig. 13, which indication also means that I may have the entire rod 5 or any desired portion of it flat.

In further explanation of the rod joints it will be understood that when a train enters upon the track portion provided with my device the first stirrup 86 reached will 10 cause a pulling of all the rod sections as if they were an integral rod from the stirrup to the yoke 52 (or 52^a) and each car wheel passing over the first stirrup operates it and the signal; and when the train has passed 15 over the first section of the rod and gets into contact with the next stirrup the latter will operate only the remaining rod sections between the train and the signal or yoke 52 and the rod sections the train has passed 20 over become idle because the pulling of the next section ahead of it can not push on the idle section owing to the slidable joint in each channel piece 63. Thus in Fig. 10 if shaft 70 is rocked by a stirrup at the 25 other side of the rail the arm 69 will pull at rod section 58^R but leaves section 58^L idle, but a stirrup (not shown) further to the left pulling at section 58^L will pull section 58^R also, because of the finger 67. 30 The weight 84 serves to hold the stirrup 86 normally in elevated position and the red board 43 when in rotation draws attention and thereby warns persons on the road 17 that a train is approaching. At the same 35 time the bell 20 is sounded to give audible alarm in case fog, mist or darkness hinders seeing the red signal.

What I claim is:

1. In a danger signal for railway crossings, a post fixed near the crossing, a rotatable signaling element mounted on the post and having a ratchet wheel, a mechanism box secured at the outer side of one of the track rails, a horizontal rock shaft having 40 one end in the mechanism box and there fixed to it two diametrically opposite radial cams, two horizontal yokes reciprocated each by one of the cams, in one direction, and by a spring in the other direction, a guided operating rod extended from each yoke, a suitable distance along the rail in opposite direction of the spring action, a series of spaced devices secured on the rail and having operative connection with the adjacent 45 operating rod, and an element for a wheel rolling on the track to press on and impart a pulling movement to the rod; said rock shaft having at the signal post a rocker arm, a vertically disposed rod arranged to be pushed upward by said rocker arm and come down again of its own weight, a dog 50 actuated by the vertical rod and arranged to engage and rotate the ratchet wheel and thereby the signalling element.

2. The structure specified in claim 1 and 65 means for automatically disengaging the dog from the ratchet wheel after each imparted push to the wheel.

3. The structure specified in claim 1, in which the vertical rod is encircled by a pushing coil spring between the rocker arm and an obstruction, secured on the rod. 70

4. The structure specified in claim 1, in which the devices operated by the track wheels are active only when operated by the 75 wheels approaching the crossing.

5. The structure specified in claim 1, in which all the parts of the signal apparatus connected directly to the rail are clamped thereon so as to be adjustable on and removable from any part of the rail. 80

6. The structure specified in claim 1, in which each operating rod is made up of several sections having slidably overlapped ends with means at said ends for one section 85 to pull but not to push the other section.

7. The structure specified in claim 1, in which each operating rod is made of several sections having slidably overlapped ends 90 with means at said ends for one section to pull but not to push the other section, a small frame placed at the outer side of the rail and guiding said overlapping, jointed ends of the rod sections, a larger frame extending across the base of the rail and having lugs taking over the inner base flange of the rail, L-shaped bolts extending through said larger frames and having nuts at the inner side of the frame and the short arms 100 of the bolts engaged with the small frame so as to clamp both frames firmly to the rail; said larger frame having a lateral wing and a clearance opening through it, between the wing and the rail flange, a 105 weighted lever pivoted to the wing and a T-shaped stirrup pivotally suspended on the lighter end of the lever and having its leg normally suspended above the said clearance; a rock shaft journaled in the top of the larger frame and having one rocker arm projecting partly into the clearance and another rocker arm at the other side of the rail arranged to pull at some part of the joint of the rod sections when a car wheel 110 passes over the stirrup.

8. The structure specified in claim 1, and a bell mounted on the post and having a clapper operatively connected with the vertical rod actuating the dog. 115

In testimony whereof I affix my signature. 120
JOHN LAUBE.
